UNITED STATES PATENT OFFICE.

FRED C. LELFIELD, OF SILVER CREEK, NEW YORK, ASSIGNOR TO COLUMBIA POSTAL SUPPLY COMPANY, OF SILVER CREEK, NEW YORK, A CORPORATION OF NEW YORK.

MAIL-MARKING MACHINE.

1,077,408.

Specification of Letters Patent. Patented Nov. 4, 1913.

Application filed November 24, 1911. Serial No. 662,199.

To all whom it may concern:

Be it known that I, FRED C. LELFIELD, a citizen of the United States, residing at Silver Creek, in the county of Chautauqua and 5 State of New York, have invented new and useful Improvements in Mail-Marking Machines, of which the following is a specification.

This invention relates to a machine for 10 canceling or post marking letters, postal cards and other mail matter.

It is the object of this invention to produce an improved machine of this character in which the die on the printing wheel re- 15 mains constantly in its retracted or inoperative position when no letter is present at the printing position and which is so organized that when a letter is at the printing position the die on the printing wheel 20 will be shifted through the medium of the letter into its operative position and cause an impression of the die to be produced on the letter as well as effecting a release of the letter from a stop device and cause the 25 letter to be fed forward to the stacking mechanism.

In the accompanying drawings consisting of 3 sheets: Figure 1 is a top plan view of a mail canceling machine or marker em- 30 bodying my improvements, showing one position of the printing wheel. Fig. 2 is a fragmentary top plan view of the machine, partly in section, showing another position of the printing wheel. Fig. 3 is a top plan 35 view of the printing wheel, impression roller, stop device and adjacent parts, showing the printing wheel and stop device in a position different from that indicated in Figs. 1 and 2. Figs. 4 and 5 are fragmentary vertical transverse sections in the correspondingly numbered lines in Figs. 1 and 40 2. Fig. 6 is a horizontal section in line 6—6, Fig. 7, looking downwardly. Fig. 7 is a fragmentary rear side elevation of the 45 machine. Fig. 8 is a top plan view of the printing wheel, on an enlarged scale. Figs. 9 and 10 are fragmentary horizontal sections, on an enlarged scale, taken in lines 9—9 and 10—10, Fig. 4, respectively. 50 Similar characters of reference indicate corresponding parts throughout the several views.

1 represents the frame or base of the machine which is provided on its upper side 5 with a horizontal table having a feed end

or portion 2 which is adapted to hold a stack of letters 3 or other mail matter to be canceled and a receiving end or portion 4 upon which said letters or other mail matter are adapted to be stacked after they have been 60 canceled or post marked.

5, 6 represent the front and rear sections of an upright guide wall lengthwise of the front and rear parts 2, 4 of the table.

The pack of letters or other mail matter 65 to be canceled or post marked is arranged against the front side of the guide wall section 5 at the feed end of the table and are held against this wall by means of a follower 7 which is preferably pivoted at one 70 end on the table at a point remote from the guide wall and yieldingly held at its free end in engagement with the letters by means of a spring 8 connected with a tail 9 on the pivoted end of the follower. The 75 lower edges of the letters preferably rest by gravity on an endless traveling apron or feed belt 10 which operates to feed the entire pile forwardly. The feed belt passes at its front and rear ends around rollers 11, 80 12 journaled in suitable bearings on the base of the machine, as shown in Fig. 7. Each of the letters is fed off from the pile on the feed end of the table and carried forwardly by an individual feed mechanism to the 85 printing mechanism which operates to produce a post mark on the same. This individual feeding mechanism may be variously constructed but that shown in the drawings is preferred and comprises a plurality of feed 90 rollers 13, 14 which are turned in such a direction that when the same engage with the foremost letter in the supply stack this letter will be carried to the printing mechanism. Two sets or pairs of such feeding 95 rollers are arranged side by side and mounted upon upright shafts 15, 16 journaled in suitable bearings on the frame of the machine. These two shafts are caused to turn together and in the same direction by means 100 of an idler pinion 17 mounted on the underside of the frame or base and engaging with gear wheels 18, 19 at the lower ends of the shafts, 15, 16, as shown in Figs. 6 and 7. Motion is imparted to the feed belt 10 from 105 the shaft 15 by means of intermeshing bevel gear wheels 20 interposed between the shaft 15 and the shaft of the front roller 11 of this belt, as shown in Fig. 7.

In order to prevent more than one letter 110

at a time from being fed away from the supply stack or pile of uncanceled letters a separating device is provided which is preferably constructed as follows: 21 represents 5 a separator arranged opposite the operative portion of the front feeding off rollers 14 and separated therefrom by an intervening space, passageway or throat of sufficient width to permit of the passage of but one 10 letter at a time but acting to hold back the remaining letters of the supply stack. This separator has an inclined face so that the front edges of the letters upon approaching the same are wedged or moved toward the 15 guide wall section 5 and the faces of the adjacent feeding off rollers 13, 14. This separator is mounted upon a horizontally swinging rock arm 22 which is pivoted on the upper side of the frame or base and the 20 same is yieldingly held in the path of the supply stack of letters by means of a tension device which comprises a guide or shifting rod 23 pivoted at its inner end to the separator and sliding at its outer end in a stationary lug 24 rising from the base, and a 25 spring 25 surrounding the shifting or guide rod and bearing at one end against a collar 26 on this rod and at opposite ends against said lug 24. The movement of the separator 30 toward the front feeding off rollers or wheels 14 may be regulated for varying the distance between the same, this being preferably effected by means of a screw nut 27 applied to the outer end of the shifting rod 35 and bearing against the outer side of the lug 24, as shown in Figs. 1 and 2.

As each letter is fed off from the supply stack it is moved forwardly to the printing mechanism which embodies my improvements and which is constructed as follows: 40 28 represents an impression roller which is arranged on one side of the path of the letters or other mail matter as they issue from the feeding off mechanism and which is 45 mounted upon the upper end of a shaft 29. For the purpose of enabling the impression roller to adapt itself to letters or mail matter varying in thickness the shaft 29 is mounted in a bearing 30 which is movable 50 toward and from the letter path, its bearing being preferably arranged at the free end of a horizontally swinging arm 31 which is pivoted on a stationary arbor or pin 32 secured vertically to the base or frame of the 55 machine. The impression roller is yieldingly held in its operative position toward the letter path by means of a spring 33 interposed between the arm 31 and a lug 34 on the upper side of the frame. The movement of this roller toward the letter path 60 may be adjusted to suit the particular character of the mail matter which is operated upon, the preferred means for this purpose consisting preferably of an adjustable stop 65 screw 35 working in a lug 36 on the upper

side of the base or frame and engaging with the front or inner side of the rock arm 31, as shown in Figs. 4 and 5.

On the lower end of the stationary arbor is mounted a driving pulley 37 which is 70 driven from any suitable source by means of a belt 38. Motion is transmitted from this pulley to the shaft of the impression roller by means of a gear wheel 39 turning with this pulley and meshing with a pinion 40 at 75 the lower end of the impression roller shaft. This pulley is also provided with a pinion 41 which meshes with the gear wheel 19 for transmitting motion to the feeding off rollers 13, 14 and the feed belt 10, as shown in 80 Figs. 6 and 7. On the opposite side of the letter path transversely in line with the impression roller is arranged a printing wheel 42 which is secured to the upper end of a shaft 43 journaled in a bearing on the adjacent part of the base or frame. This shaft is turned together with its printing wheel in the direction of the arrow in Figs. 3 and 8 by means of an intermediate or idle gear wheel 44 journaled on the underside of the 85 frame and meshing with the gear wheel 39 and a gear wheel 45 secured to the lower end of the printing wheel shaft.

46 represents a horizontally swinging die arm or carrier arranged on the upper side 90 of the printing wheel and pivoted at its rear or trailing end by means of a vertical pin 47 to a bracket 48 on the upper side of the printing wheel. On the outer side of its free front end this carrier or die arm is provided with one or more dies 49, 50 which 95 are adapted to print canceling lines, dates and post office marks on the letters or other mail matter. When the die arm is retracted or moved inwardly relatively to the axis of rotation of the printing wheel its printing dies do not move through the path of the letters between the printing wheel and the impression roller. But when this die arm is swung outwardly into its operative position 100 the faces of the dies are caused to sweep through the letter path and engage with a letter which is passing forwardly between the printing wheel and impression roller for producing an impression of the dies on 105 the letter. The faces of the die are coated with ink by means of a roller 51 mounted on the upper side of the base or frame adjacent to the outer side of the printing wheel 110 in position to be engaged by the dies during 115 the rotary movement of the same with the printing wheel. This retraction of the die arm out of its printing position and projection into the printing position relatively to the printing wheel is controlled by the 120 letters which are fed forward from the supply stack to the printing mechanism. This letter actuated mechanism is so organized 125 that when a letter is in the printing position the dies will be projected so as to produce 130

an impression on the letter but when no letter is present in the printing position the dies are retracted so as to avoid transferring ink from the same to the impression roller which otherwise would cause the backs of the letters to become smeared with ink. The preferred means for thus effecting the retraction and projection of the dies into their inoperative and operative position is constructed as follows: 52 represents an upright trip shaft journaled in a bearing on the printing wheel substantially diametrically opposite to the point where the die arm is pivoted to the printing wheel and provided with an eccentric or cam 53 which engages with a slot 54 in the front or free end of the die arm. At its upper end the trip shaft is provided with an elbow shaped rock or trip lever the outer arm 55 of which forms a feeling or trip finger which projects rearwardly from this shaft while its inner arm 56 forms a restoring tail which projects radially inward from the trip shaft, as shown in Figs. 1, 2 and 3. This trip lever is adapted to be turned so that its feeling or trip finger either projects laterally beyond the periphery of the printing wheel, as shown in Fig. 1, or is substantially concentric with the printing wheel and flush with the periphery thereof, as shown in Figs. 2 and 3. The trip lever is yieldingly held in either one or the other of these two positions by means of a yielding retaining device which preferably comprises a cam 35 formed on the trip shaft and having a central high part 57 and two flat low parts 58, 59 on opposite sides of the high part, as shown in Fig. 9, and a retaining lever 60 pivoted on the printing wheel and having one arm arranged to engage the retaining cam while the other arm is connected by means of a spring 61 with said printing wheel. When no letter is present in the printing position and the trip finger is projecting laterally from the printing wheel, as shown in Figs. 1 and 8, the retaining or detent lever engages with the low face 58 of the retaining cam on the inner side of the high part 57 of the same, as shown in Fig. 9. When a letter is present at the printing position the trip finger engages with this letter and is shifted thereby from its laterally projecting position shown in Figs. 1 and 8 to a position in which it is substantially concentric with the periphery of the printing wheel, as shown by full lines in Figs. 2 and 3 and by dotted lines in Fig. 8. During this rotation of the trip lever the high part 57 of the retaining cam deflects the retaining lever 60 and brings the other low part of this cam into engagement with this lever, whereby the pressure of the spring 61 is caused to yieldingly hold the trip finger in its retracted position. As the trip finger engages with a letter at the printing position and is moved inwardly, the cam 53 on the trip shaft is turned and moves the die arm outwardly so that the dies thereof are shifted into their operative position, whereby the letter at the printing position is gripped between the impression roller and the periphery of the printing wheel and the dies, and the letter is fed forward and an impression of the dies is produced thereon. After the trip finger clears the letter at the printing position and the dies have produced their mark on the same the tail of the trip lever engages with a stationary tappet 62 arranged in the path of the tail, whereby the trip lever is turned in the direction for again projecting the trip finger into the letter path. This tappet is preferably supported over the printing wheel by means of a bracket 63 secured to the adjacent stationary part of the machine. The oscillatory movement of the trip shaft is limited by means of a stop 79 on the bracket 80 carried by the printing wheel and adapted to be engaged by stop faces 81, 82 arranged on the trip shaft on opposite sides of the axis of the same, as shown in Fig. 10.

The periphery of the printing wheel is preferably of such length that one rotation of the same will cause a letter of ordinary length to clear the same during one rotation of this wheel so that the trip finger after being again projected into its operative position by the tappet 62 will be ready to again shift the dies into their printing position for producing an impression on the next following letter which has been fed forwardly to the printing position. If, however, the letter which has just been impressed by the dies is of unusual length the trip finger, after being projected by means of the tappet 62 into its operative position, will upon engaging the trailing part of such long letter be again retracted and cause the dies to be again projected and produce a second impression on this letter. Such a second impression will, however, not occur in the case of letters of the length usually sent through the mails.

For the purpose of arresting each letter as it is fed forward from the supply stack and reaches the printing position a stop device is provided which is preferably constructed as follows: 64 represents a horizontally swinging stop arm which is pivoted at its rear end on the upper side of the frame on the same side of the letter path on which the impression roller is pivoted and provided at its free end with a stop shoulder 65 and an upwardly projecting pin or tappet 66 arranged in advance of said shoulder. In its operative position this stop arm is swung inwardly so that its stop shoulder is arranged in the letter path adjacent to the bight between the impression roller and printing wheel or substantially on a line 130

drawn through the pivots of this roller and wheel. The movement of this stop arm in this direction is limited by means of a stop 67 which is preferably constructed of rubber, 5 felt or other soft material so as to render the same noiseless and the stop arm is yieldingly held in this position by means of a spring 68 connecting a tail 69 on this arm with the frame of the machine as shown in Figs. 1, 2, 10 3 and 7. As each letter is fed forwardly from the supply stack by the feeding off mechanism its front edge engages with the stop shoulder 65 of the arm 64 and is arrested at the printing position.

15 On the underside of the outer end of the trip finger the same is provided with a depending lug or tappet 70. While the trip finger is in its laterally projecting position shown in Figs. 1 and 8 and no letter is at the 20 printing position between the impression roller and printing wheel the tappet 70 of the trip finger sweeps through a circular path the radius of which is greater than the distance from the axis of the printing wheel 25 to the tappet 66 of the stop arm so that the tappet of the trip arm clears the tappet of the stop arm and the latter is permitted to remain undisturbed with its shoulder arranged in the path of the letters. When, 30 however, the trip finger is deflected inwardly by engagement with the letter at the printing position the tappet of the trip finger is brought into a position in which it sweeps through a circular path the radius of which 35 is the same as the distance from the axis of the printing wheel to the tappet on the stop arm, whereby the tappet of the trip finger is caused to engage the tappet of the stop arm immediately after the trip finger has been 40 deflected inwardly by the letter and the stop arm is thereby pushed out of the letter path so as to permit the letter at the printing position to move forwardly between the impression roller and printing wheel and receive an impression of the dies. After the 45 stop arm has been thus deflected out of the letter path by the tappet of the trip finger and the letter has commenced its forward movement between the impression roller and printing wheel the free end of the stop arm bears against the side of the letter opposite the printing wheel and the instant the rear or tail end of the letter clears the free end of the stop arm the latter is instantly shifted 50 by its spring into its operative position in which its shoulder stands in the letter path and is prepared to intercept the next following letter.

55 As the letters issue from between the impression roller and printing wheel the same are carried forward to the stacking or receiving end of the table by means of a delivery-belt 71 having its operative stretch arranged parallel with and on one side of the letter 55 path and passing around rollers 72, 73 ar-

ranged on the upper end of the impression roller shaft and the upright stacker shaft 74 journaled in a bearing on the adjacent part of the stacker end of the table. The letters are caused to move with the operative 70 stretch of the delivery belt by means of two pressure rollers 75, 76 mounted on the frame and engaging with opposite sides of the operative stretch of the delivery belt, as shown in Figs. 1, 2 and 7. As the letters reach the 75 stacking end of the table they are engaged successively by a rotary stacking wheel 77 mounted on the upper end of a stacker shaft and moved laterally from the stacking end of the table to a rack 78 which projects laterally from this end of the table and upon which the letters are stacked or gathered after they have been marked or canceled preparatory to being removed by the mail clerk or postman.

80 I claim as my invention:

1. A mail marking machine comprising a printing wheel, a printing die movably mounted on said wheel and means operated by the mail matter for shifting said die into or out of its operative position on said wheel, said means comprising parts mounted on said printing wheel.

85 2. A mail marking machine comprising a printing wheel, a carrier movably mounted on said wheel and having a printing die for marking mail matter, a trip lever mounted on said wheel and adapted to be turned by engagement with mail matter at the printing position, and means for causing said die 90 carrier to be moved into its operative position as the trip lever is turned by the mail matter.

95 3. A mail marking machine comprising a printing wheel, a carrier movably mounted on said wheel and having a printing die for marking mail matter, a trip lever mounted on said wheel and adapted to be turned by engagement with mail matter at the printing position, and a cam turning with said 100 trip lever and operating to move said die carrier into its operative position when said lever is moved by engagement with mail matter.

105 4. A mail marking machine comprising a printing wheel, a carrier movably mounted on said wheel and having a printing die for marking mail matter, a trip lever mounted on said wheel and adapted to be turned by engagement with mail matter at the printing position, means for causing said die carrier to be moved into its operative position as the trip lever is turned by the mail matter, and means for restoring said trip lever to its normal position after clearing said 110 mail matter.

115 5. A mail marking machine comprising a rotary printing wheel, a carrying arm pivoted at its rear end on said wheel and provided with a printing die for marking mail 120 matter.

125

- matter, a trip shaft journaled on the printing wheel and provided with a shifting cam engaging with said carrying arm, and a trip lever mounted on said shaft and adapted to be turned by engaging mail matter at the printing position and cause the cam to move the die on said arm into its operative position.
6. A mail marking machine comprising a printing wheel, a carrier movably mounted on said wheel and having a printing die for marking mail matter, a trip lever mounted on said wheel and adapted to be turned by engagement with mail matter at the printing position, means for causing said die carrier to be moved into its operative position as the trip lever is turned by the mail matter, means for restoring said trip lever to its normal position after clearing said mail matter, and a retaining device for yieldingly holding said trip lever and associated parts either in their operative or in their inoperative position.
7. A mail marking machine comprising a rotary printing wheel, a carrying arm pivoted at its rear end on said wheel and provided with a printing die for marking mail matter, a trip shaft journaled on the printing wheel and provided with a shifting cam engaging with said carrying arm and also provided with a retaining cam having a high part and low parts on opposite sides of the high part, a retaining lever mounted on said wheel and yieldingly engaging said retaining cam, a trip lever mounted on said shaft and adapted to be turned by engaging the mail matter at the printing position for moving the die into its operative position, and a stationary tappet adapted to engage said trip lever after the same clears the mail matter and to return the same to its operative position.
8. A mail marking machine comprising a rotary printing wheel, a carrying arm pivoted at its rear end on said wheel and provided with a printing die for marking mail matter, a trip shaft journaled on the printing wheel and provided with a shifting cam engaging with said carrying arm and also provided with a retaining cam having a high part and low parts on opposite sides of
- the high part, a retaining lever mounted on said wheel and yieldingly engaging said retaining cam, a trip lever mounted on said shaft and having a trip arm adapted to engage with the mail matter at the printing position and a restoring tail, and a stationary tappet adapted to be engaged by said restoring tail.
9. A mail marking machine comprising a printing wheel, a printing die movably mounted on said wheel, means for moving said die into and out of its operative position comprising a trip lever mounted on said wheel and adapted to engage mail matter at the printing position and a stop adapted to be normally arranged in the path of the mail matter and to be deflected out of said path by the trip lever when the latter is shifted by engagement with the mail matter.
10. A mail marking machine comprising a printing wheel, a printing die movably mounted on said wheel, means for moving said die into and out of its operative position comprising a trip lever mounted on said wheel and adapted to engage mail matter at the printing position and provided with a tappet, and a stop arm having a shoulder adapted to normally stand in the path of the mail matter and to be deflected out of said path by the tappet of said trip lever.
11. A mail marking machine comprising a printing wheel, a printing die movably mounted on said wheel, means for moving said die into and out of its operative position comprising a trip lever mounted on said wheel and adapted to engage mail matter at the printing position and provided with a tappet, a stop arm having a shoulder adapted to normally stand in the path of the mail matter and provided with a tappet adapted to be engaged by the tappet of said trip lever for deflecting the stop arm out of said path, and means for yieldingly holding said stop arm in a position in which its shoulder stands in said path.

Witness my hand this 21st day of November, 1911.

FRED C. IELFIELD.
